United States Patent Office

Des. 211,624

Patented July 9, 1968

211,624

TIE FASTENER

Gilbert Cohen, 2383 Montview Drive NW,
Atlanta, Ga. 30305

Filed May 9, 1967, Ser. No. 7,045

Term of patent 7 years

(Cl. D2—424)

Fig. 1

Fig. 2

FIG. 1 is a front elevational view of a tie fastener showing my new design, the chain, broken away, is continuous as indicated by dash dot lines; and

FIG. 2 is a side elevational view thereof, the side opposite being reversely similar, the chain being broken away for convenience of illustration.

I claim:

The ornamental design for a tie fastener, as shown and described.
